UNITED STATES PATENT OFFICE

160,219

WHEELED TOY FIGURE OR THE LIKE

Harry Sebel, London, England

Application August 23, 1949, Serial No. 4,669
In Great Britain August 3, 1949

Term of patent 14 years

(Cl. D34—15)

To all whom it may concern:

Be it known that I, Harry Sebel, a subject of the King of Great Britain, resident of London, England, have invented a new, original, and ornamental Design for a Wheeled Toy Figure or the like, of which the following is a specification, reference being had to the accompanying drawing, forming part thereof.

I claim:

The ornamental design for a wheeled toy figure or the like, as shown.

HARRY SEBEL.
